ABSTRACT OF THE DISCLOSURE

An indicator which comprises a stack of plates each carrying on its surface a number of dates. The plates are moved in succession from one side of the stack past a window and are returned to the other side. The driving means can be a pawl or a toothed wheel mechanism. The plates have co-operating abutment means whereby a driven plate initiates movement of the next plate and then carries it to a position where it can be engaged by the driving mechanism. A driven plate always has at least one of its ends in the stack.

SUMMARY OF THE INVENTION

This invention relates to an indicator. The invention relates more particularly, but not exclusively, to an indicator for indicating the date on a watch or clock.

It is an object of the invention to provide an indicator which is compact and reliable in operation.

To this end there is provided an indicator comprising a plurality of thin plates disposed in a stack and driving and guiding means adapted to cause the plates to move in succession past a reading position, the plates being taken from one side of the pile and returned on the other side of the stack, wherein the improvement comprises driving and guiding means adapted to drive a plate situated partly outside the pile by engaging a part of the plate that is free from the stack and by making it slide along the adjacent plate in the stack during its withdrawal from the stack, and abutment means on each plate adapted to co-operate with abutment means on the adjacent plate so that the driven plate pulls the adjacent plate with it before such driven plate is completely free from the stack, whereby to bring the adjacent plate in its turn within range of the driving means.

BRIEF DESCRIPTION OF DRAWINGS

Other objects and advantages of the invention will become apparent from the following description of exemplary embodiments given with reference to the appended drawings, in which:

FIGURE 1 is a plan view of a first embodiment of indicator according to the invention, this embodiment forming a date-indicator in a watch or clock;

FIGURE 2 is a section along the line 2—2 in FIGURE 1;

FIGURES 3 and 3a are diagrammatic views illustrating the operation of the indicator in FIG. 1;

FIGURES 4 and 4a show details of a pawl driving mechanism of the indicator in FIG. 1 on a larger scale and in two different operating positions;

FIGURE 5 is a perspective view of a detail of a plate sector of the indicator in FIG. 1;

FIGURE 6 is a diagrammatic representation of the indicator in FIG. 1;

FIGURES 7, 8, 9 and 10 are diagrammatic representa-

2

tions of other embodiments of indicator according to the invention;

FIGURES 11, 12 and 13 are views of a variant of the driving mechanism of the indicator in FIG. 1 in three different operating positions;

FIGURE 14 shows in diagrammatic form a detail of an indicator comprising plates stacked in the form shown in FIG. 8;

FIGURE 15 is a partial plan view of a variant of the driving mechanism of the plates of an indicator comprising plate sectors;

FIGURES 16, 17 and 18 are perspective views of different attachment means for connecting the plates;

FIGURES 19 and 20 are diagrammatic plan views of series of plates attached by the means shown in FIGS. 17 and 18;

FIGURES 21 and 22 are diagrammatic views showing variants of the indicator in FIG. 1.

DESCRIPTION OF PREFERRED EMBODIMENTS

The date-indicator shown in FIGS. 1 to 6 comprises, under a watch or clock face shown diagrammatically at 1, four thin plates sectors 2a, 2b, 2c and 2d disposed in a stack on a support 3. These plates sectors are intended to move past a window 1a of the face 1.

The four plates sectors have in plan the form of annular sectors of the same diameter. They are disposed around an inner ring 4 rigidly secured to the face 1, and are movable round this ring as explained hereinafter.

The inner arcuate edges of the plates 2 have regularly spaced recesses 5. These recesses 5 are adapted to co-operate with a driving pawl 6 disposed at one end of a loop spring 7, the other end of which is secured at 8 to a barrel wheel 9 rotating at the rate of 1 revolution every 12 hours.

The pawl 6 bears resiliently on the inner wall 10 of the ring 4 (FIG. 4). But this ring 4 has an aperture 11 in which two recesses 5 of the plate sectors can appear. When the pawl 6 passes opposite the aperture 11 it falls into the first uncovered recess 5 and drives the engaged plate sector through an angle corresponding to the angular spacing of adjacent recesses before returning to the ring (FIG. 4a).

The aperture 11 is situated in an angular position such that the pawl 6 rotates the engaged plate sector at noon and midnight by an amount corresponding to one spacing of the recesses on each occasion.

In the position shown in FIG. 1 the pawl 6 co-operates with the plate sector 2a. This plate extends over an arc of 305° and as shown occupies the position A.

The other three plate sectors 2b, 2c, and 2d, which are at rest in the position shown in FIG. 1, are then in the superimposed position and occupy the arc B. Each plate sector when returned to the bottom of the stack at the end of its movement past aperture 11 by the pawl 6 is left in this angular position B.

In the arc C corresponding to the clear space between the ends of the three superimposed plate sectors 2b, 2c and 2d, the plate sector 2a, which is in the top position in the left part of FIG. 1, flexes downwardly to pass under the stack so that it is below the other plate sectors in the right part of the figure. The plate sector 2a driven by the pawl 6 is thus caused to pass progressively from the top to the bottom of the stack as shown diagrammatically in FIG. 6.

In the angular position shown in FIG. 1, a number "22" on the plate sector 2a is opposite the left half of the window 1a; this window extends over an arc corresponding to two recesses 5. Driving through one spacing at noon will bring this number "22" into the right half of the window, i.e. without changing the date. On the succeeding

advance at midnight the number "23" will appear in the window 1a and will remain there for twice 12 hours.

In a variant of the indicator the window 1a may extend over an arc corresponding to a single recess 5, each of the numbers then being carried twice on the plate sectors, so that the first appears from midnight to noon and the second from noon to midnight. The numbers visible in the morning and those that are visible in the afternoon may be in different colours.

At its rear end the plate sector 2a has a stop 12 projecting from its lower surface (FIG. 3) and situated on the same circumference as a stop 13 situated at the front end of the plate sector 2b and projecting from the upper surface of that plate (FIG. 3). These stops 12 and 13 are formed, for example, by a projection punched out of the plates (FIG. 5).

Thus, when the stop 12 of the plate sector 2a engages the stop 13 of the plate sector 2b the latter plate is driven after the plate 2a (FIG. 3a).

FIG. 3 shows the passage of the plate sector 2a past the window 1a while that plate alone is being driven. FIG. 3a shows the stage in which the plate 2b carried along with the plate 2a and is thereby driven after the plate 2a.

As coupling between two successive plates takes place while the leading plate still overlaps the led plate, the second plate is directed under the pile even in the absence of other guide means.

The plate sectors may be of the same or different lengths. In the example shown the 31 possible dates are, for example, distributed over two sectors of 15 recesses 5 and over two sectors of 16 recesses 5, or in all over an arc of 62 recesses advancing at the rate of 2 recesses a day.

The four-plate indicator that has just been described enables an arc of about 20° to be given to each date on the plates, whereas if the 31 dates were on a single disc the arc available for each date would be only about 11° for a disc driven every 24 hours or about 5.5° for a disc driven at noon and midnight. A date-indicator may thus be more easily provided on watches of small diameter than previously.

By multiplying the number of plates the number of items of information may also be increased, and the plates may be in the form of thin sheets, of metal ribbon, plastics or paper for example, so that the overall size of the stack is small.

In the indicator described with reference to FIGS. 1 to 6 the advance of the plate sectors is gradual and passage from one date to another extends over an appreciable time.

In a variant of the indicator driving mechanism shown in FIGS. 11, 12 and 13, the pawl for driving the plate sectors is adapted to actuate the latter abruptly and in jerks.

In this variant a barrel wheel 20 drives a pawl 21 disposed at the rear end of a loop spring 22 secured to an arm 23 pivoting with a limited angular play on a hub 20a of the wheel.

The pawl 21 has a front nose 24 adapted to co-operate with the recesses 25 of the plate sectors 26 and a rear nose 27, which is smaller than the nose 24 and is adapted to engage in an auxiliary recess 28 of a fixed ring 29.

When the pawl 21 pulled by the spring 22 falls into the first uncovered recess 25a the rear nose 27 engages in the auxiliary recess 28 (FIG. 11). The wheel 20 then continues to rotate, stretching the spring 22, until the end 23a of the arm 23 abuts on the rear part 21a of the pawl, so that the latter is released from the auxiliary recess 28. The released pawl 21 is then abruptly pulled forward by the spring 22 and rapidly drives the plate sector through one angular distance before returning to the ring 29 (FIG. 12).

In the mechanism that has just been described the arm 23 is driven by means of lost-motion coupling formed by

an arm 30 projecting radially from the side of the hub 20a of the wheel 20 and co-operating according to the direction of rotation with one or other of the ends 31, 32 of the central part of the arm 23,

The arm 30 drives the arm 23 in the normal operating direction indicated by the arrow F; a finger 34 on the pawl 21 then remains beyond the reach of a hook 33 of the arm 30 (FIG. 11). But if the arm 30 is caused to turn in the opposite direction the hook 33 comes under the finger 34 of the pawl and then retains the latter radially (FIG. 12).

Thus a rearward rotation of the wheel 20 and the arm 30 may be effected without the pawl 21 retained by the hook 33 falling into the recesses of the plate sector (FIG. 13). When rotation is resumed in the forward direction F the pawl 21 is released from the hook 33. This enables the date to be adjusted easily by forward or rearward rotation.

In another variant of the driving mechanism shown in FIG. 15 a wheel 40 rotating once every 12 hours engages with a wheel 41 whose diameter is twice as large, so that such wheel 41 rotates once every 24 hours. The wheel 41 has a catch 42, which actuates in the course of its movement a toothed wheel 43 permanently engaged with teeth 44 cut in the inner edge of the plates 45. A bar biased into engagement with the wheel 43 keeps the wheel 43 in its stop position.

In the embodiment shown in FIG. 7 the rectangular plates, disposed on edge, form a stack in the form of a sector of a hollow cylinder.

In the embodiment shown in FIG. 8 the plates, each in the form of an annular sector, are guided so as to pass from one side to the other of the stack by turning over. FIG. 14 shows a detail of this. The top plate 46, which moves past a window 47, is pulled from the stack 48 by a pawl driving mechanism shown diagrammatically at 49. This mechanism causes the plate to move forward step by step, and the plate is guided in a hairpin slot 50, which returns it under the pile.

This turning over is also effected in the embodiments in FIGS. 9 and 10, in which the rectangular plates are stacked respectively in the form of a sector of a hollow cylinder and a prismatic stack.

In these last three embodiments indications on both sides of the tablets are therefore caused to move past a window or any other form of reading means.

In FIGS. 16, 17 and 18, different forms of abutment means for the attachment of successive ones of the plates are shown. In the form shown in FIG. 16, the ends of the plates are bent back to form hooks 51 and 52. In the form shown in FIG. 17, the ends of the plates are cut in the form of dovetails. To prevent the simultaneous driving of several superimposed plates, one plate is provided with two female dovetails 53, while the next plate has two male dovetails 54 (FIG. 19). Thus each plate can only be coupled with the adjacent plate.

In the embodiment shown in FIG. 18 the abutments means are formed by slightly raised tongues 55 formed on the edge of an aperture 56 cut out of the plate. In this variant, to prevent the simultaneous driving of several plates, the paired abutment means are disposed alternately on the right and left edges of the plates as shown in FIG. 20.

With the hooks shown in FIG. 16 or the tongues shown in FIG. 18, the end parts of the coupled plates remain in the superimposed position and the stack of plates occupies a little more space. With the dovetails (FIG. 17) the plates are flat and are placed end to end, occupying the minimum amount of space.

According to the attachment means used, passage from one side of the stack to the other can be effected without special guides, as shown diagrammatically in FIG. 21, or along a continuous guide, as shown in FIG. 22.

Owing to the small overall size of an indicator embodying the invention a date-indicator for the whole year

may be provided in a watch or clock, i.e., an indicator having 365 successive positions.

The indicator according to the invention may also be used in a clock or watch to provide information other than the date. It may also be used for purposes other than clocks or watches with driving means of other types. Thus the plates may for example show the departure times of the successive trains serving a given line, while electromagnetic actuating means enable the indicator to be remote-controlled so as to change the indication given after the departure of each train.

According to another application the plates may carry photographic plates and move past a projector.

I claim:

1. An indicator comprising a plurality of thin plates disposed in a stack and driving and guiding means adapted to cause the plates to move in succession past a reading position, the plates being taken from one side of the pile and returned on the other side of the stack wherein the improvement comprises driving and guiding means adapted to drive a plate situated partly outside the pile by engaging a part of the plate that is free from the stack and by making it slide along the adjacent plate in the stack during its withdrawal from the stack, and abutment means on each plate adapted to co-operate with abutment means on the adjacent plate so that the driven plate pulls the adjacent plate with it before such driven plate is completely free from the stack, whereby to bring the adjacent plate in its turn within range of the driving means.

2. An indicator according to claim 1, wherein the plates are disposed flat and the guiding and driving means are adapted to move the plates from one side of the stack to the other as a result of rotation of the plates about an axis that is approximately perpendicular to their plane.

3. An indicator as claimed in claim 2, wherein the plates are in the form of annular sectors.

4. An indicator as claimed in claim 3, wherein each plate is in the form of an annular sector which extends over an arc greater than 180° and the axis of rotation passes through the centre of curvature of each annular sector so that a plate, during transfer, always has at least one of its ends in the stack.

5. An indicator as claimed in claim 1, comprising generally rectangular plates disposed on edge in a stack in the form of a sector of a hollow cylinder and wherein the driving and guiding means are adapted to move the plates from one side of the stack to the other as a result of a rotation about an axis corresponding approximately to that of the stack.

6. An indicator as claimed in claim 5, wherein the stack extends over an arc greater than 180° so that a

plate during transfer always has at least one of its ends in the stack.

7. An indicator as claimed in claim 1, comprising generally rectangular plates disposed in a prismatic stack and wherein the driving and guiding means are adapted to move the plates from one side of the pile to the other along a hairpin path.

8. An indicator as claimed in claim 7, wherein the developed length of the path along which the plates are moved is shorter than the length of the plates so that a plate during transfer always has at least one of its ends in the stack.

9. An indicator as claimed in claim 1, wherein the driving means comprise a rotatable pawl adapted to co-operate with teeth cut in one edge of the plates, such pawl sliding against the wall of a guide ring having an aperture bounding a limited arc for driving the plate, the teeth in the one edge of a driven plate being engaged only when the pawl passes the aperture so as to cause the plate to advance step by step.

10. An indicator as claimed in claim 9, wherein the pawl is driven by means of a resilient member and comprises an element adapted to retain the pawl momentarily in order to stretch the resilient member, the arrangement being such that the engaged plate advances abruptly through the arc corresponding to the aperture in the guide ring on the release of the resilient member.

11. An indicator as claimed in claim 9, wherein the driving means comprise retaining means engageable with the pawl for holding the pawl in an inoperative position while it crosses the aperture in the guide ring.

12. An indicator as claimed in claim 11, wherein the retaining means is arranged automatically to engage the pawl when it is driven to the rear.

13. An indicator as claimed in claim 1, wherein the abutment means are formed by attachment means adapted to connect the plates end to end without superimposition of the assembled plates.
